UNITED STATES PATENT OFFICE.

SUMNER A. BEMIS, OF SPRINGFIELD, MASSACHUSETTS.

CAR-AXLE BOX.

SPECIFICATION forming part of Letters Patent No. 239,018, dated March 22, 1881.

Application filed July 26, 1880. (No model.)

To all whom it may concern:

Be it known that I, SUMNER A. BEMIS, of Springfield, in the county of Hampden and State of Massachusetts, have invented a new and useful Improvement in Axle-Boxes for Railway-Cars, (which has not been patented to me nor to any one in any foreign country with my knowledge and consent,) of which the following is a specification.

The object of my invention is to provide a car-axle box which is convenient of access, uniform and even in the bearing and wear of its movable parts, strong and durable, and which shall permit an easy motion of the car-body with which it is connected; and I accomplish these objects by the mechanism shown in the accompanying drawings, which is an improvement upon the patent granted to me September 4, 1877, No. 194,801.

Figure I is a side view of a car-axle box having my invention applied. Fig. II is an end view of the same. Fig. III is a vertical longitudinal section at the axis of the axle. Fig. IV is a half plan view of the pedestal and box together, and a half plan view of the box alone, and Fig. V is a plan view of the brass which takes the bearing of the axle.

In the drawings, B represents the box proper, or that portion which contains the oil, and in which are located the bearing portions of the axle, and upon the lower side of the upper portion of which is cast a lug, 3, (shown in Fig. III,) which lug projects down by the side of the stud 2 on the brass 16, to stop the latter from moving inward out of place, the key 4 at the outer end of the axle preventing the brass from moving outward, and this forked key 4, which is movable in vertical grooves 17 in the sides of the box, also straddles the grooved outer end of the axle and keeps the latter in its proper relative position with and in the box.

The cap C is provided at its upper end with a projection, 8, on the inside, which is inserted into a recess, 10, in the upper side of the box, near its outer end, and the cap is provided with a recess, a, with a hole in the bottom, to receive a bolt, 1, inserted down through the

outer end of the box, with a nut turned on the lower end, which secures the cap in place upon the box.

The pedestal D is secured to the sill E (shown in dotted lines) of the car by bolts b, and is provided with jaws D', which extend down over each side of the box B, and a spring, F, is secured to the inner end of each bolt b by check-nuts 11, and extends down on each side of the box, with its lower end arranged to bear against the housing A and its upper part to bear against a lug, 5, cast upon the inside of the upper part of the pedestal, and the spring is prevented from vibrating in one direction—that is, in a direction lengthwise the car—by the lugs or projections 6 on the pedestal. This spring may be adjusted to bear more or less against the housing A by turning the nuts 11 more or less onto the bolts b. The steps 7—one on each side the box to support the spring—are each secured by two braces—one, as at I, extending from the step to the box, and the other, as at I', extending from the step to the housing A, which construction renders the whole much stronger and much more rigid.

The brass 16, which sustains the bearing of the axle H, is made with both ends alike, so that the brass may be inserted either end first, and its ends are elongated, with a hole, 18, in each, if desirable, by which to draw the brass out of the box conveniently with a hook when the cap C is removed for that purpose.

Having thus described my invention, what I claim as new is—

1. The combination of the axle, having no brass-retaining collar of greater diameter than its bearing-surface, with the box, adapted to contain the axle and its bearings, provided with a single lug, as 3, projecting down inside, and a movable brass provided with a single stud, as 2, projecting upward to bear against said lug, substantially as and for the purpose set forth.

2. The combination, in an axle-box for cars, of the box adapted to contain the axle, the housing for the same at the inner end of the box, a step on each side the box to support the car-spring, and two braces extending in

different directions from each step, one to the box and the other to the housing, and made solid therewith, substantially as described.

3. The combination of the spring F, with retaining-nuts, as 11, the pedestal provided with lugs, as 6, to prevent side vibration of the spring, the lug 5 as a bearing for said spring, and the box, with its housing, for containing the axle, substantially as described.

10 4. The reversible brass, provided with a sin-

gle stud, as 2, to operate in connection with a single lug, as 3, projecting down from the axle-box above, and formed with elongated ends, each having a hole therein, substantially as and for the purposes set forth.

SUMNER A. BEMIS.
